(57) **CLAIM**

The ornamental design for a light fixture, as shown and described.

DESCRIPTION

This application is related to commonly owned concurrently filed U.S. design patent applications Ser. No. 29/197,587, Ser. No. 29/197,600, Ser. No. 29/197,613, Ser. No. 29/197,608, and Ser. No. 29/197,619.

FIG. 1 is a front elevational view of the light fixture of the present design, a rear elevational view being a mirror image thereof;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top plan view of an alternative embodiment of the light fixture shown in FIG. 4;

FIG. 7 is a front elevational view of an alternative embodiment of a light fixture of the present design, a rear elevational view being a mirror image thereof;

FIG. 8 is a left side elevational view thereof;

FIG. 9 is a right side elevational view thereof;

FIG. 10 is a top plan view thereof;

FIG. 11 is a bottom plan view thereof; and,

FIG. 12 is a top plan view of an alternative embodiment of the light fixture shown in FIG. 10.

The broken lines shown are for illustrative purposes only and form no part of the claimed design.

1 Claim, 12 Drawing Sheets
